UNITED STATES PATENT OFFICE.

HENRY CLAY LYONS, CHARLES ROMAINE CLARK, AND WILLIAM T. MCLEAN, OF ALEXANDRIA, VIRGINIA.

PUMP.

No. 904,208.

Specification of Letters Patent.

Patented Nov. 17, 1908.

Application filed September 11, 1907. Serial No. 392,295.

To all whom it may concern:

Be it known that we, HENRY CLAY LYONS, CHARLES ROMAINE CLARK, and WILLIAM T. MCLEAN, citizens of the United States, residing at Alexandria, in the county of Alexandria and State of Virginia, have invented certain new and useful Improvements in Pumps; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to force pumps but more particularly to that class of rotary pumps in which an eccentric movement of the pistons is employed for forcing air, water or other liquid from the pump.

Our invention has for its object to provide a device of this class which is so constructed and arranged that a great volume of air, water or other liquid can be forced by the pump with a very slight eccentric movement of the pistons.

A further object of our invention is to provide a pump of large capacity and of a comparatively small size.

30 A further object of our invention is to provide a pump of the character specified which is so constructed and arranged that the extent of movement of the pistons can be readily adjusted either for the purpose 35 of taking up wear or for the purpose of making the pump applicable for use in pumping and forcing sand and water.

40 A further object of our invention is to provide a pump of the character specified which is so constructed and arranged that the extent of eccentric movement of the pistons can be adjusted without disconnecting the pump or without taking the same apart.

A further object of our invention is to 45 simplify the construction of the driving shaft and adjustable eccentric bushing.

A further object of our invention is to 50 protect the shaft and eccentric bushing from the water in the pump.

50 A further object of our invention is to provide means for allowing the pressure of the discharge water to act upon the back of the piston to hold same in its proper relative position.

A further object of our invention is to 55 provide means for preventing the pounding of the piston rings against the dividing wall.

A further object of our invention is to 60 provide a more desirable and convenient location of the intake and discharge ports.

With all these objects in view our invention consists in the arrangement of the shaft and the adjustable eccentric bushing and 65 pistons which prevents the access of water to the shaft and adjustable eccentric bushing.

Our invention further consists in a construction which provides for leading a portion of the discharge water or fluid behind the piston exerting pressure thereon to hold 70 the same in its proper relative position.

Our invention further consists in the arrangement of a guide pin in the back of the piston for holding the piston rings from 75 pounding against the dividing wall.

Our invention further consists in coring the pump in such manner that a more convenient location of the ports is attained.

Our invention further consists in providing a pump so that the same can be utilized 80 as an air pump of any number of stages.

Referring to the accompanying drawings: Figure 1 is an elevation of the stationary pistons. Fig. 2 is a transverse sectional view taken on line 2-2 of Fig. 1. Fig. 3 is a vertical transverse sectional view through the pump taken on line 3-3 of Fig. 4. Fig. 4 is a vertical sectional view taken on line 4-4 of Fig. 3. Fig. 5 is a vertical sectional view taken on line 5-5 of Fig. 3. Fig. 6 is a rear elevation of the rear plate or 85 wall of the pump. Fig. 7 is a rear elevation of the eccentric pistons. Fig. 8 is a front elevation of the same.

Like numerals of reference indicate the 90 same parts throughout the several figures in which:

1 indicates the pump which comprises the stationary pistons 2 which are arranged on the front wall or casing 3 of the pump.

4 indicates the eccentric pistons which are arranged on a wall or plate 5 (Figs. 7 and 8).

6 indicates the rear wall or plate of the pump, and 7 the shell to which the front and 100 rear walls or plates 3 and 6 are secured, preferably by means of screws or bolts 8, as shown in Fig. 4. It will be seen from this

figure that the shaft 9 has an eccentric enlargement 10 thereon while a rotatable bushing 11 is arranged on the eccentric enlargement 10. The rotatable eccentric bushing 11 is provided with a rear wall 12 and a central opening to receive a screw or bolt 13 which is threaded into the eccentric enlargement 10 of the shaft 9. It will also be seen from Fig. 4 that the eccentric pistons 4 are mounted on the eccentric bushing 12, and that the wall or plate 5 of said pistons is threaded to receive a cap 14.

Referring to the rear wall or plate 6 of the pump it will be seen that the same is centrally threaded to receive a cap 15, said cap being of such a size as to permit removal of the cap 14 in order to rotate the eccentric bushing 11 on the eccentric enlargement 10 of the shaft 9 in order to adjust the eccentric pistons. It will also be seen from Fig. 4 that the rear plate or wall 6 is provided with a vertical groove 16 (also shown in Fig. 6), while the wall or plate 5 of the eccentric pistons 4 is provided with a pin or extension 17 which enters the said groove 16.

Referring to Fig. 3 it will be seen that the shell 7 of the pump is cored at 18 and 19, the core 18 communicating with a port 20 at the top of the pump and also communicating with a port 21 at the bottom of the pump, while the core 19 communicates with similar ports 22 and 23.

Referring now to Fig. 1 it will be seen that the stationary pistons 2 connect with one another by means of two cored passages 24 and 25, said cored passages being clearly shown in Fig. 2, a central web 29 being employed to divide the cored passages 24 and 25.

40 It will be seen from Fig. 5 that the cored passage 24 communicates with the space between the stationary pistons 2 by means of suitable ports 27, while a port 28 connects the cored passages 24 and 25 with the cored passage 18 in the shell of the pump; this being clearly shown in Figs. 3 and 5.

29 indicates a dividing wall arranged as shown in Figs. 1 and 3, while the eccentric pistons 4 are each provided with a slot 30 in order to allow said pistons to straddle the dividing wall or partition 29 as shown in Fig. 3.

Referring now to Figs. 5 and 6 it will be seen that a threaded port 40 connects the cored passage 18 with a cored passage 41 in the rear plate or casing 6 of the pump (Fig. 6). It will also be observed from Fig. 6 that a similar cored passage 42 is provided, which by means of a threaded port 40 (Fig. 2) connects the cored passage 19 (Figs. 2 and 3) with the cored passage 42, the port 40 and cored passage 41 being to one side of the center of the pump while the port 40 and cored passage 42 are to the other side of the center of the pump.

From Fig. 5 it will be seen that the cored passage 42 communicates with the space in rear of the plate or wall of the eccentric pistons.

Having thus fully described our invention its operation is as follows: The parts are assembled as shown in the drawing and the pump can be run in either direction. When utilizing, however, port 21 (Fig. 3) as the intake the ports 20 and 23 are plugged as shown allowing the water to discharge through port 22. When running the pump in the reverse direction the ports 21 and 22 are plugged, the ports 23 and 20 becoming the intake and discharge ports. Considering, however, the port 21 as being the intake, the water or fluid enters said port and passes into the lower portion of the cored passage 18 (Fig. 5); from the cored passage 18 it passes through the port 28 into the cored passage 24 along the front wall or casing 3 of the stationary pistons 2 entering between the pistons through the ports 27. By means of the eccentric action of the pistons 4 the water or fluid is forced from the dividing wall or partition 29 around the pistons to the opposite side of the dividing wall or partition 29 where it is discharged through the ports 27 into the cored passage 25 (Fig. 2), then through the port 28 into the cored passage 19 (Figs. 2 and 3) being forced up said cored passage 19 discharging through the port 22.

Referring now to Fig. 5 it will be seen that the port 40 entering the cored passage 19 allows a portion of the discharge water to pass through said port 40 into the coring 41 in the rear plate 6 of the pump; from the coring 41 it passes upwardly between the rear plate 6 and the plate or wall 5 of the movable pistons 4; thus the pressure of the discharge acts upon the plate or wall 5 of the eccentric pistons 4 to hold said pistons in their proper relative position, thus insuring a tight and efficient pump. When the water is being forced into the passage 42, the port 40 leading to the passage 41 is plugged as shown in Fig. 2, and when the passage 41 is receiving water, the port 40 leading to passage 42 is plugged.

It has been found that the eccentric movement of the movable pistons causes them to strike violently against the dividing wall or partition 29, thereby creating considerable noise. In order to obviate this difficulty and render the pump noiseless we provide the groove 16 (Figs. 4 and 6) within which is a guide pin or extension 17 on the plate or wall 6 of the eccentric pistons 4. This guide pin being directly in rear of the dividing wall or partition 29 allows the pistons a free vertical movement at this point and prevents any lateral movement sufficient to allow the pistons to engage the vertical wall or partition 29.

Should it be desired to alter or adjust the eccentric pistons the same is accomplished by removing the cap 15 from the rear plate or wall 6 of the pump (Fig. 4) 5 then removing the cap 15 in the plate or wall 5 of the eccentric pistons 4. By means of a suitable wrench the bolt or screw 13 is loosened allowing the rotatable bushing 11 to be rotated on the eccentric enlargement 10 of the shaft 9. By this construction a very neat and fine adjustment of the pistons can be effected, the extent of adjustment 15 obviously depending upon the character of the work to which the pump is to be subjected.

It will be seen from Fig. 4 that the eccentric bushing 11 being provided with a wall 12 and the plate or wall 5 of the eccentric pistons 4 being provided with the cap 14 all 20 water or fluid is excluded from the shaft and eccentric bushing. As pumps of this character are frequently employed for pumping water having considerable sand and grit therein it is at once apparent that the life of 25 the pump, and particularly the shaft and bushing, is very materially lengthened by excluding the water laden with sand or grit from these rotating parts.

Having thus fully described our invention what we claim as new and desire to secure by Letters Patent of the United States is,—

1. A pump of the character described, comprising one or more stationary pistons and 35 one or more movable pistons associated therewith, a shell or casing for said pistons, said shell or casing being provided with two cored passages, each cored passage partially surrounding the said pistons; a partition at 40 opposite points of said shell or casing for separating the said two cored passages, each cored passage terminating in an intake port at one end and a discharge port at the other, a port communicating with each of said 45 cored passages for leading the water to and from said pistons, the whole arranged in such manner that the discharge from the pistons passes into one of said cored passages and is led partially around said pistons be-

fore being discharged from the shell or casing, substantially as described. 50

2. A pump of the character described, comprising a suitable shell or casing, a removable wall or plate on said casing, one or more stationary pistons and one or more movable 55 pistons arranged within said casing, an eccentric within said casing, an eccentric bushing on said eccentric upon which said movable pistons are mounted, a plate carrying said movable pistons, a cover on said plate 60 covering said eccentric and eccentric bushing, and a removable cap on the wall or plate of said shell or casing opposite the said cover on said plate carrying said movable pistons, the whole arranged in such manner 65 that said cover and said cap are removable for adjustment of said eccentric bushing on said eccentric.

3. A pump of the character described, comprising a suitable shell or casing, one or more 70 stationary pistons and one or more movable pistons arranged therein, an eccentric, an eccentric bushing on said eccentric upon which said movable pistons are mounted, a plate carrying said movable pistons, and 75 means for preventing access of fluid to said eccentric and eccentric bushing.

4. A pump of the character described, comprising a suitable shell or casing, one or more stationary pistons arranged therein, one or 80 more movable pistons associated with said stationary pistons, a shaft entering said casing, an eccentric on said shaft, an eccentric bushing on said eccentric, said movable pistons being mounted on said eccentric bushing, a plate carrying said movable pistons and a cover on said plate covering said eccentric and eccentric bushing to prevent 85 access of fluid to said eccentric and eccentric bushing, substantially as described. 90

In testimony whereof, we affix our signatures, in presence of two witnesses.
